By Brown & Nissen Attys.

UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

INSULATOR.

Application filed April 10, 1919. Serial No. 289,091.

To all whom it may concern:

Be it known that I, ARTHUR O. AUSTIN, a citizen of the United States, residing at Barberton, in the county of Summit and

5 State of Ohio, have invented certain new and useful Improvements in Insulators, of which the following is a specification.

This invention relates to insulating devices and especially to insulating devices 10 designed for use with high potentials, and has for its object the provision of insulators which shall provide improved mechanical strength for the amount of material employed without sacrificing electrical efficiency and which shall be of improved construction and operation.

The invention is exemplified in the combination and arrangement of parts shown in the accompanying drawing and described 20 in the following specification, and it is more particularly pointed out in the appended claims.

In the drawing, the figure represents an insulator embodying one form of the present invention shown partly in elevation and partly in section.

In the embodiment shown, the dielectric or insulating material is in the form of a hollow tube 1 which is represented as being 30 of uniform diameter throughout. The tube 1 may, however, be of various shapes to give strength and convenience in manufacture.

Various insulating materials may be employed, one material in common use being 35 porcelain and other vitreous materials, such as glass, are sometimes employed. Connected with the tube, adjacent the opposite ends thereof, are hollow metallic members 2 and 3 which are provided with eyes or 40 other fastening devices 4 and 5, respectively, by means of which the insulator is secured to the parts to be insulated. The member 2 is intended to be connected with the grounded support while the member 3 is connected 45 with the charged conductor. The members 2 and 3 are secured to the tube 1 at points spaced from the ends of the tube, as shown at the left in the drawing. The joint between the cap 3 and the tube 1 may be effected in any of the usual and approved 50 ways for making such connections, it being common practice to employ a high grade of Portland or other cement for this purpose, as shown at 6 in the drawing. The

surfaces of the tube 1 and the cap 3, which 55 are engaged by the cement, are preferably roughened to insure firm connection with the cement.

Under certain conditions of operation the tubular insulator is very desirable for the 60 reason that a tubular section gives a highly efficient distribution of the material to resist bending strains set up by vibration of the insulator and connected parts and for other reasons. It has been found, however, 65 that where tubular insulators are employed there is a tendency to discharge through the center of the tube and especially is this true if moisture collects within the tube.

It is very desirable to avoid such a central 70 flash-over or discharge, for the reason that a discharge through the tube almost invariably results in an explosion of the tubular member the least disastrous effect of which is the destruction of the insulator. An outside discharge, however, is usually accompanied by little or no damage. Where connecting caps are secured directly to the ends of a tube insulator any discharge or flash-over is very apt to take place through the 80 center of the tube for the reason that the path through the center is as short or shorter than the outside path and for the reason that atmospheric conditions within the tube are likely to be such as to offer less resistance 85 to a discharge than the atmosphere outside the tube. A baffle or web of insulating material may be extended across the tube for the purpose of decreasing the liability of discharge through the center, but under certain 90 conditions this barrier may defeat its own purpose. If, for instance, moisture accumulates within the tube, then practically the entire drop of potential between the ends 95 of the tube occurs in the short space occupied by the baffle web, for the reason that this web is approximately an infinite resistance compared with the resistance of the remaining portion of the interior of the tube, and as a result the entire pressure is concentrated upon the web and the web is 100 pierced and an internal discharge results. Such a cross web also interferes with the flow of charging or leakage current through the center of the tube which tends to dry 105 any moisture which accumulates within the tube. A web of this kind also interferes with the circulation of atmosphere within

the tube and tends to set up atmospheric conditions favorable to flash-over.

In the present invention the tendency to discharge through the center of the tube is overcome by connecting the end cap at a point spaced inwardly from the end of the tube and by forming the cap so that every point thereof is located at a considerable distance from the opening at the mouth of the tube. The cap may be shaped so that approximately all the points of the cap will have the same resistance between them and the mouth of the tube. This means that the point of contact between the cap and the tube is spaced a greater distance from the end of the tube than the points in the cap nearer the end of the insulator. The reason for this is that any leakage from the point of contact between the cap and the tube will extend along the surface of the tube instead of across an air-gap. A discharge from points opposite the open end of the tube must pass through the air space between the cap and the tube, and hence the space between the cap and the end of the tube at these points need not be so great as points adjacent the contact between the cap and the tube. A discharge from any intermediate point in the cap would probably take place partly through the air and partly along the surface of the tube so that the cap would gradually diverge from the surface of the tube as it extends toward the end of the insulator. A cap designed, therefore, to give an approximately uniform resistance to flash-over from various points in the cap to the center of the tube would have a shape similar to that shown in the drawing. This shape also is desirable from a mechanical standpoint as it is well suited to withstand the stress placed upon the cap by the tension exerted upon the eye 5. It will be understood, of course, that other shapes of connecting cap may be employed without sacrificing the benefits of resistance due to the spacing of the walls of the cap from the end of the tube. For instance a cylindrical cap could be used connected to the tube by wall members at its inner end extending inwardly to the tube at right angles to its axis, and various other shapes could be employed.

It is desirable for many reasons that a free circulation of air through the center of the insulator may be possible, for otherwise the air within the insulator may be affected by the electrical stresses so as to produce pressure within the insulator, or to decrease the resistance to flash-over. Also, circulation of the air through the insulator facilitates drying of the interior of the tube and thus decreases the tendency to leakage and discharge. To permit free circulation of air within the interior of the insulator, breathers designated by the numeral

7 may be connected with the end caps 2 and 3, these breathers being constructed to exclude water from the interior of the insulator but to permit free passage of air. The end of the breather tube 7 may be enclosed in a chamber 8 having peripheral perforations 9 through which water may escape independently of the position of the insulator and the tube 7 preferably extends a short distance into the chamber 8 and is provided at its end with a circumferential bead 10 to collect water of condensation and prevent its entering the insulator through the tube 7.

The flash-over of a high tension insulator depends to a great extent upon the distribution of electro-static flux of lines of force and where a concentration of the electro-static lines of force is permitted there is danger of a power discharge along the path of these lines of force. It is therefore desirable to distribute the electro-static flux as nearly evenly as possible in order to prevent a concentration of the lines of force at one point. For this reason an electro-static screen, shown at 11 in the drawing, is connected to the end cap 3 and extends outwardly from its point of connection with the end cap and toward the opposite end of the insulator. The electro-static screen 11 is preferably made of open construction having arms 12 which carry a uniformly curved circular rim 13 at their forward ends, the rim 13 surrounding the tube 1 and spaced radially from the tube. With this arrangement the electro-static flux is caused to emanate substantially uniformly from the surface of the rim 13 so that there is no concentration of the flux at any one point with a consequent tendency to flash-over from that point. The open construction of the screen permits of washing by rain and hence the screen is kept clean by its exposure to the weather.

While the connectors 2 and 3 are shown in the drawing as solid shells, they may, of course, be of open or skeleton construction without losing the advantage of having the parts of the connectors spaced from the ends of the tubular insulator member. When an open construction is used, the breathers will of course not be necessary.

I claim:

1. An insulator comprising a tube of insulating material having an open end and a pair of connecting members secured to the outer surface of said tube adjacent the opposite ends thereof and insulated from one another, one of said members being arranged to engage said tube only at points adjacent to and spaced from said open end.

2. An insulator comprising a tube having an opening extending entirely therethrough, and a pair of connecting members secured to the outside of said tube and insulated from one another, one of said members be-

- ing arranged to engage said tube only at points spaced inwardly from the open end thereof.
3. An insulator comprising a tube having the end thereof open, and a pair of connecting members secured to the outside of said tube and insulated from one another thereby, one of said members being arranged to engage said tube only at points spaced inwardly from the open end thereof, said connecting member having all points thereof spaced from the end of said tube.
4. An insulator comprising an integral elongated insulating member having an opening therethrough, and a mechanical connector cap disposed entirely externally of said member and secured to said member adjacent one end thereof, said cap having all of the points thereof spaced from the end of said insulating member.
5. An insulator comprising a tubular insulating member having the end thereof open, and a mechanical connector cap secured to said member adjacent said end, said cap being disposed entirely externally of said member and arranged to surround the open end of said member and having the walls thereof spaced away from the end of said member.
6. An insulator comprising a tubular insulating member having an open end, and an external connector secured externally to said member at a point spaced inwardly from said end, said connector extending from its point of connection with said insulating member outside of said member past said end and having all points thereof spaced from said end.
7. An insulator comprising a unitary tubular insulating member having a free passage extending therethrough, end caps secured to the outside surface of said member and enclosing the ends of said member and having the walls thereof spaced from the ends of said members at all points of said walls.
8. In an electric insulator, an insulating mechanical load carrying member comprising a unitary tube of vitreous material having an opening extending therethrough, and external mechanical load carrying metal end caps secured to said tube externally thereof and adjacent the ends thereof, said caps having the walls thereof spaced from the ends of said tube, said tube being the only mechanical connection between said end caps.
9. An insulator comprising a tubular insulating member, an end cap secured to said member at a point spaced inwardly from the end thereof, the walls of said cap being shaped to diverge outwardly from said insulating member and to extend toward and surround the end thereof so that all points in the walls of said cap are spaced from the end of said member at distances to effect approximately uniform resistance to flash over between the various points in the walls of said end cap and the open end of said tubular insulating member.
10. An insulator comprising a tube of insulating material having an open end and a pair of connecting members secured to the outer surface of said tube adjacent the opposite ends thereof and insulated from one another, one of said members being arranged to engage said tube only at points adjacent to and spaced from said open end, and a flux distributing screen secured to one of said connecting members and extending outwardly from said tube and toward the opposite end of said member.
11. An insulator comprising a tube having an opening extending entirely therethrough and a pair of connecting members secured to the outside of said tube and insulated from one another, one of said members being arranged to engage said tube only at points spaced inwardly from the open end thereof, and an electrostatic screen secured to said connecting member and extending toward the opposite end of said tube and outwardly therefrom.
12. An insulator comprising a tube having the end thereof open, a pair of connecting members secured to the outside of said tube and insulated from one another thereby, one of said members being arranged to engage said tube only at points spaced inwardly from the open end thereof, said connecting member having all points thereof spaced from the end of said tube, and an electrostatic screen secured to said connecting member and extending toward the opposite end of said tube and outwardly therefrom, said screen having a curved rim surrounding said tube at the portion of said screen farthest removed from said connecting member.

In testimony whereof I have signed my name to this specification on this 3rd day of April, A. D. 1919.

ARTHUR O. AUSTIN.
